UNITED STATES PATENT OFFICE.

ROBERTA ELLIOTT, OF HOMESTEAD, PENNSYLVANIA.

DESIGN FOR AN ENVELOP-BLANK.

SPECIFICATION forming part of Design No. 34,464, dated April 30, 1901.

Application filed March 26, 1901. Serial No. 52,973. Term of patent 14 years.

To all whom it may concern:

Be it known that I, ROBERTA ELLIOTT, a citizen of the United States of America, residing at Homestead, in the county of Allegheny and State of Pennsylvania, have invented and produced a certain new and original Design for an Envelop-Blank, of which the following is a specification, reference being had therein to the accompanying drawing.

This invention relates to a certain new and original design for an envelop-blank; and it consists of a blank of the shape and configuration shown in the accompanying drawing, in which I illustrate my invention in plan view.

The leading feature of the design consists of a substantially rectangular body portion 1 and substantially V-shaped end flaps 2, of a width corresponding to the width of the body

portion 1, and back flap 3, provided along each edge with V-shaped incisions 4 and flap 5, and a substantially square flap or wing 6; the latter having a centrally-arranged square opening 7. The free edge of the flap 5 is at an angle with the horizontal line, and the free edge of the body portion 1 is likewise at an angle to the horizontal line to the envelop.

What I claim as new, and desire to secure by Letters Patent, is—

The design for an envelop-blank, as herein shown and described.

In testimony whereof I affix my signature in the presence of two witnesses.

ROBERTA ELLIOTT.
